UNITED STATES PATENT OFFICE

FRED BOARD, OF BRIDGEPORT, OHIO

CURRENT COLLECTOR FOR TROLLEY WIRES

Application filed December 4, 1929. Serial No. 411,487.

This invention relates broadly to electrical current collectors or take-offs, and it has for its primary object to provide an improved form of device whereby temporary connection may be made with trolley wires or other forms of high tension electric wires for taking off current for use in operating electric motors or other devices or apparatus.

A further object of the invention is to provide a device of the character mentioned, designed especially for use on trolley wires, which makes electrical or current collecting contact with the under side of the wire, which side is at all times maintained in a polished, or noncorroded, condition by the frequent engagement therewith of the trolley wheels of passing electric cars.

A still further object is to provide a device of the character mentioned which, following application in operative relation to the trolley wire, is yieldingly maintained in such close contact with the polished under side of the trolley wire that there is practically no possibility of the wire becoming pitted, or burned, through the production of an arc or arcs between the wire and the contact member of the device, as frequently occurs when the contact member of prior forms of take-offs of this type seat upon, or imperfectly contact with, the corroded top surfaces of wires.

In describing the invention in detail, reference is herein had to the accompanying drawings, in which—

Figure 1 is a side elevation of the invention applied to a trolley wire;

Figure 2 is a rear elevation of the same;

Figure 3 is a front elevation; and—

Figure 4 is a fragmentary section on line 4—4, Fig. 2.

Referring to said drawings, 1 designates the pole, which may have any appropriate length. Said pole carries upon its upper end a sleeve 2 which has spot welded thereon, as shown at 3, or otherwise suitably attached thereto the lower end portion of a plate 4. Said plate 4 is bifurcated above said sleeve, forming upright arms 5 having angularly disposed rearwardly directed parallel terminals 5^a which, in practice, are adapted to be

placed in overlying seated relation to a trolley wire 6 for suspending the entire structure from said wire.

Designed to cooperate with the two terminals 5^a is a metal contact member 7, preferably copper, adapted to seat in underlying relation to the wire, said member being of substantially U-shape in cross section. Said member 7 is carried in rigid relation to and is insulated from the upper end of a vertically shiftable rod or bar 8. As herein shown, a block 9 of fiber, or other suitable material which is a non-conductor of electric current, is interposed between said contact member 7 and the bar 8, being rigidly mounted on said bar, as by a rivet or bolt 10, and having said member rigidly mounted thereon, as by a rivet or bolt 11, as shown. Said bar, which is disposed vertically with its upper end portion located between the supporting arms 5 hereinbefore referred to, is vertically movable in recesses or guideways 12 and 13 provided therefor in the horizontally disposed members of angular brackets 14 and 15, respectively, which are suitably mounted in appropriate positions on the rear face of the plate 4.

For maintaining said bar 8 normally in an upwardly thrust position wherein it holds the thereby supported contact member 7 in firmly seated relation to the under side of the trolley wire 6, suitably resilient means is provided. Said means, as herein shown for illustrative purposes, comprises a pair of vertically disposed retractile coil springs 16 which have their upper ends attached in fixed relation to said plate 4, as to the opposite ends of the bracket 14 carried by said plate. A crossbar 17 fixed to said bar 8 at a suitable point has the lower ends of said springs attached to the opposite ends thereof, as shown. The springs 16 normally exert a force which, when the device is applied to a trolley wire, acts to maintain the contact member 7 firmly seated against the under side of the wire. To provide for retraction of said contact member to the extent that the wire may be received between, or disengaged with relation to, the contact member and the terminals 5^a, a lever 18 pivotally mounted on the pole 1

at a suitable point; and a suitable connection, as a cable 19, is introduced between said lever and the lower end of the bar 8. As is manifest, downwardly directed manual force applied to the outer end of the lever acts against the tension of the springs 16 to draw the bar downward and thus to retract the contact member from its normal position. So retracted, the device may readily be applied to or removed from the trolley wire.

10 One terminal 20 of an electrical conductor or wire 21 is suitably attached to the contact member 7 and the opposite terminal 22 of said conductor is mounted upon a binding post which consists of a bolt 23 carried by and projecting from an insulating plate 24 which is attached to the plate 4, as by means of bolts 25. A second current conductor 26 leads from said post 23 to the motor or other device which 20 is to be actuated.

15 It will be noted that, because of the fact that the contact member 7 is made of considerable length and that the terminals 5^a overlie the trolley wire at a distance from the 25 opposite ends of said contact member, a wide bearing is afforded, thus reducing to a minimum the tendency of said bearing to rock with respect to the trolley wire and, consequently, practically eliminating all chance 30 of production of arcs which might otherwise result.

20 What is claimed is—

25 A current collector of the character described comprising a pole, an upright plate 35 carried in rigid relation to said pole, upright arms carried by said plate, said arms having angularly disposed parallel terminals for occupying overlying seated relation to an electric wire, a vertically slidable bar having its 40 upper end disposed between said arms, brackets carried by said plate constituting guides for said bar, a contact member carried by said bar, said member having a length materially exceeding the width of said bar and 45 being adapted to seat upon a substantial length of the under side of the wire between said terminals, retractile coil springs having their upper ends attached to one of said guide brackets and their lower ends connected 50 to said bar whereby the latter is normally held in elevated position presenting said member in underlying engagement with the wire, and means for manually retracting said bar, 55 said means including a lever pivoted on said pole and a connection between said lever and said bar.

In testimony whereof, I affix my signature.
FRED BOARD.
